UNITED STATES PATENT OFFICE.

ARTHUR J. WELLS, OF SYRACUSE, NEW YORK.

PAPER OR BILL FILE.

SPECIFICATION forming part of Letters Patent No. 386,674, dated July 24, 1888.

Application filed September 9, 1887. Serial No. 240,199. (No model.)

To all whom it may concern:

Be it known that I, ARTHUR J. WELLS, of 5
Syracuse, in the county of Onondaga, in the
State of New York, have invented new and
useful Improvements in Paper or Bill Files, of
which the following, taken in connection with
the accompanying drawings, is a full, clear, and
exact description.

My invention relates to improvements in
knockdown portable paper-files, and has for
its object the production of a simple and effect-
ive file-rack which may be placed on a table
or desk or in any desirable position for use and
the partitions or compartments for the papers
adjusted to any desirable dimension in width;
and to this end the invention consists, essen-
tially, in a base provided with perforations
and a series of partitions adapted to be united
to the base by placing the same in the perfo-
rations at intervals, as desired.

It also consists in the detail construction and
arrangement of the parts, all as hereinafter
more fully described, and pointed out in the
claims.

25 In specifying my invention reference is had
to the accompanying drawings, forming a part
of this specification, in which, like letters in-
dicating corresponding parts in all the views—

Figure 1 is an isometric view of my improved
30 paper-file set up for use. Fig. 2 shows a trans-
verse section through the base, illustrating the
manner of uniting the partitions to the base.
Fig. 3 shows a modification in the construc-
35 tion of the partitions. Figs. 4 and 5 are de-
tails of the modification, the base being in sec-
tion; and Fig. 6 illustrates a further modifica-
tion in the construction of the partition and
its attaching devices for uniting it to the base.

40 A denotes the base of my improved paper-
file. The same consists of a suitable support,
preferably made of hard wood and having a
metal plate, D, secured to the top thereof, the
said metal plate being provided with perfora-
tions C, extending in series at intervals through-
45 out the length of the base A. The said perfora-
tions form seats or sockets which receive
the legs of the partitions B and support the
same in their operative position. The parti-
tions B are preferably made of wire, and con-
50 sist of the bends or legs a b c, the bends a
and c, respectively, being formed of spring-
wire, so as to have a slight outward bend,

which, when the partition B is united to the
base by inserting the bends or legs a b c in the
perforations C, the outward tendency of the 55
spring supports the leg firmly in the seat, while
at the same time the perforation may thereby
be somewhat larger than the bends or legs of
the wire partition, and consequently the leg
may be easily inserted in the base. 60

It will be observed that by reason of the per-
forations extending lengthwise of the base in
series the partitions B may be inserted in the
base at any required distance apart, thus al-
lowing the compartments between the parti-
tions to be made of any suitable width, and
thereby an efficient adjustable paper-file is
produced, which is of great utility in a mer-
cantile office or counting-room in filing tem-
porarily memoranda which require further 70
correspondence or some intermediate delay in
disposing of the same before the memoranda
are filed away for reference, and my invention
produces a desirable device for this purpose,
for the reason that it occupies very little space 75
and may be readily adapted to the require-
ments without difficulty, and at the same time
presents an attractive appearance and is du-
rable.

I do not restrict myself to the specific con-
struction of my invention as illustrated in
Figs. 1 and 2, since the top plate, D, of metal
may be dispensed with and rows of perfora-
tions C formed, respectively, in the sides of
the base A, as best shown in Figs. 3, 4, and 5. 85
In this case, however, it is desirable to pro-
vide guides f, which are formed at right an-
gles to the perforations C and extend from the
top of the base into the perforations, and to
bend the spring-arms a and c of the partitions 90
B at right angles, as best shown at e, Figs. 4,
5, and 6, and when the partitions are united
to the base the angular bends of the spring-
arms a and c are simply pulled out or bent
outwardly and inserted by putting the ends 95
in the guides f and pushing them down until
the ends e enter the perforations C, when the
spring of the metal forces them in the perfora-
tions. In this construction I preferably
make the partition B of sheet metal, as shown 100
in Fig. 6, attaching the flanged base d to the
lower edge thereof, and secure the spring-wire
arms a b to the side edges of the partition B,
as best shown at Fig. 6, and it will be observed

that the flanged base *d* affords an efficient support to the partition without detracting from the simplicity of construction or its efficiency in use, while the spring-arms *a b* make a secure lock in connection with the perforations *C* and firmly secure the partition *B* to the base *A*.

My improved paper file or rack may be detached and packed very closely for shipment, 10 and, being simple in construction, can be produced very economically and affords an efficient device for the desired purpose.

Having thus fully described my invention, what I claim as new, and desire to secure by 15 Letters Patent, is—

1. The herein-described paper-file, consisting of a base adapted to lie upon a desk or table and formed with a series of perforations, and adjustable partitions provided with steps 20 removably fitting into the perforated base, substantially as and for the purpose set forth.

2. The combination of the base *A* and perforated plate *D*, secured to its top, and the adjustable partitions *B*, having the steps *a c*, adapted to enter the perforations, substantially as and for the purpose set forth. 25

3. The base *A*, formed with a series of perforations, *C*, and the adjustable partitions *B*, having the spring-steps *a c*, substantially as specified. 30

In testimony whereof I have hereunto signed my name, in the presence of two attesting witnesses, at Syracuse, in the county of Onondaga, in the State of New York, this 5th day of September, 1887.

ARTHUR J. WELLS.
